CLAIM

The ornamental design for a plurality of reaction vessels with lids, as shown and described.

DESCRIPTION

This application is related to U.S. Design patent application Ser. No. 29/437,592, filed Nov. 19, 2012, which claims priority to Japanese Design Application No. 2012-26294, filed Oct. 29, 2012, the entire disclosures of which are incorporated herein by reference.

FIG. 1 is a perspective view of a plurality of reaction vessels with lids showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof; and,

FIG. 8 is a perspective view thereof shown in a closed configuration.

1 Claim, 5 Drawing Sheets
